UNITED STATES PATENT OFFICE.

GEORGE HAVILAND, OF LIMOGES, FRANCE.

DESIGN FOR A COVERED DISH OR SIMILAR ARTICLE.

Application filed November 4, 1925. Serial No. 15,341 Term of patent 3½ years.

To all whom it may concern:

Be it known that I, GEORGE HAVILAND, a citizen of the United States, residing at Limoges, France, have invented a new, original, and ornamental Design for a Covered Dish or Similar Article, of which the following is a specification, reference being had to the accompanying drawings, forming a part thereof, and in which—

Fig. 1 is a side elevation, and

Fig. 2 is a top plan view of the article showing my new design.

I claim:

The ornamental design for a covered dish or similar article, as shown.

GEORGE HAVILAND.
